5 Claims. (Cl. 126—140)

The present invention relates to a closure device and more particularly to a closure device utilized to open and close the area of a portable fireplace screen.

In prior fireplace screens, a wire mesh material is usually supported by a frame so as to extend across the fireplace opening, this wire mesh in some instances being hung like a curtain so that the mesh can be drawn to one side or the other for permitting easy access to the fireplace. It will be appreciated, however, that while wire mesh of this type is useful for preventing a certain portion of the sparks emitted by the fire from passing through the screen, that it is not effective for preventing all the sparks from passing through the screen and that soot can freely pass therethrough. Screens of this type are further objectionable in that a wire mesh to a great extent obstructs the vision of the fire. The closure device of the present invention contemplates a pair of panels which are supported relative to a pair of stationary panels located respectively at the top and bottom of the fireplace screen frame to move from a closed position to an open position, in the open position the opening being of a size sufficient to permit easy access to the fireplace. These movable panels are preferably constructed of any suitable heat-resistant transparent material such as glass so that a fireplace screen of this type has all the utility of a screen employing wire mesh besides completely insuring against the passing of sparks through the screen and the emission of smoke therethrough. A screen of this type also has the aesthetic consideration that the viewer's view of the fire is not hindered or distorted in any manner.

It is, therefore, an object of the present invention to provide a closure device for moving two panels from each other while guiding the movement of the panels.

Another object of the invention is to provide a portable fire place screen having movable transparent panels which do not obstruct the view and which are easily moved apart.

A still further object of the invention is to provide a portable fireplace screen having movable panels and means for moving the panels in unison in opposite directions in such a manner that the panels are easily movable from their closed position to their open position relative to the fireplace screen.

These and other objects of the invention not specifically stated above will become readily apparent from the accompanying description and drawings in which:

Fig. 1 is a front elevational view of a fireplace screen incorporating the novel closure device of the present invention.

Fig. 2 is an elevational view of a section of the back of the fireplace screen shown in Fig. 1, slightly enlarged.

Fig. 3 is a horizontal sectional view taken along the line 3—3 of Fig. 2, slightly enlarged and showing details of construction.

Fig. 4 is a horizontal sectional view taken along the line 4—4 of Fig. 2, slightly enlarged and showing details of construction.

2

Fig. 5 is a horizontal sectional view taken along the line 5—5 of Fig. 2, slightly enlarged and showing details of construction.

Fig. 6 is a vertical sectional view taken along the line 6—6 of Fig. 2, slightly enlarged and showing details in construction.

Fig. 7 is a vertical sectional view taken along the line 7—7 of Fig. 2, slightly enlarged and showing details in construction.

10 Fig. 8 is a perspective view of the back side of the screen diagrammatically illustrating the panels and linkage mechanism in closed position.

Fig. 9 is a perspective view similar to Fig. 8 showing the panels and linking mechanism in open position.

15 A fireplace screen embodying the principles of the present invention is illustrated in Fig. 1 and designated broadly by the number 10 and comprises a suitable frame 11 which consists of a pair of upright side members 12 and 13 and a top member 14. Members 12, 20 13 and 14 are preferably angular shaped in cross-section and the vertical side of top member 14 overlaps the front surface of side members 12 and 13 and is secured thereto by rivets 15. Vertically disposed legs 17 of a rigid U-shaped reinforcing member 16, see Fig. 2, 25 are secured by suitable bolts 18 to each of the side members 12 and 13 adjacent the lower ends thereof and serve to rigidly tie the frame members together at the bottom.

30 The screen 10 has a stationary bottom panel 19 and a stationary top panel 20 which are vertically spaced from one another and define the opening of the screen. The bottom stationary panel extends across the bottom of the frame and is composed of a center section 21, 35 an upper section 22, and a lower section 23, the upper and lower sections 22 and 23 being in overlapping relationship with respect to center section 21 and center section 21 having its top and bottom edges curled so as to provide rigidity thereto, see Fig. 7. The opposite 40 ends of center section 21 are secured to the front surface of each of the side members 12 and 13 by bolts 24 and a spacer 25 is positioned between the center section and the front surface of each of the side members so as to prevent buckling of the front section. The upper and lower sections are likewise secured at their 45 opposite ends to the front surface of side members 12 and 13 by bolts 26 and 27. A pair of suitable braces or legs 28 are secured by bolts 24 and 26 so as to support the screen in a substantially vertical position.

50 The top stationary panel 20 is preferably formed of heat-treated glass and its opposite ends are received in L-shaped supporting brackets 29, only one of which is visible, which are secured at their ends to the front surface of each of the side members 12 and 13 by bolts 30. It will be appreciated, therefore, that top panel 55 20 is rigidly supported adjacent the upper end of frame 11.

An upper movable panel 31 and lower movable panel 32 are likewise supported in frame 11 and are likewise 60 preferably composed of heat-treated glass, upper panel 31 being carried so that in one position its upper edge just overlaps the lower edge of panel 20 and the lower panel 32 being carried so that in one position its upper edge just overlaps the lower edge of panel 31 and its lower edge just overlaps the upper edge of panel 19. In this one position, therefore, it will be apparent that 65 panels 31 and 32 are capable of completely closing the front of the screen opening.

The opposite ends of each of the movable panels 31 and 32 are supported in mounting brackets 33, see Fig. 4, and since each of these mounting brackets is identical 70 in construction, the description of one will apply to all of them. Bracket 33 is preferably in the form of an

extrusion of any suitable light metal such as aluminum and comprises in the present instance a channel portion 34 having a pair of spaced apart sections 35 and a neck section 36. One end of panel 31 or 32 is received between sections 35 and the sections are urged together so as to grip the panel end. To insure against the panel sliding out of the channel section 34, a suitable pin 37 is received by sections 35 adjacent the bottom end thereof.

The neck section 36 has formed therein a pair of guideways 38 which, as will be more fully appreciated hereinafter, support the bracket for guided up-and-down movement on a guide channel 39. The neck also has formed thereon a clevis 40 which is fastened in any suitable manner at its opposite ends in an endless chain 41.

It will be appreciated, therefore, that mounting bracket 33 is so designed that brackets of identical construction can be used for mounting the opposite ends of panels 31 and 32 in spaced apart overlapping relationship and the brackets 33 for supporting panel 32 are in end-over-end position with respect to brackets 33 for supporting panel 31 so that clevises are in opposed relationship and the channel sections, which are displaced to one side of the centerline, are in spaced-apart relationship.

As best seen in Figs. 2 and 7, a guide channel 39 is secured adjacent its upper end by a bolt 42 to side member 12 and a spacer bar 43, which also serves to make the frame more rigid, and adjacent its lower end by a bolt 44 which receives thereon suitable spacers 45 and bolts 18. A guide channel 39 is likewise secured to side members 13 in an identical manner, not visible.

A rigid shaft 46 is rotatably carried in suitable slings 47 which are secured to the upper surface of top member 14 by rivets 48, only one of which is visible, and the opposite ends of shaft 46 have suitable gear wheels 49 fixed thereto which are positioned in vertical alignment with the open top of their respective guide channel 39. A pulley 50 is rotatably mounted in each of the guide channels 39 in vertical alignment with its associated gear wheel 49 on a bolt 51 which in turn is threadedly received in a leg 17 of member 16 and a washer 52 centers the pulleys for rotation in their respective channels.

Chain 41, as previously suggested, is in the form of an endless belt which is trained around the pulley and its associated gear wheel of each of the guide channels 39, the links of the chain intermeshing with the teeth of the gear wheel 49 so as to cause the shaft to rotate when the chain is moved thereon. It will be appreciated, therefore, that one flight of each of the chains moves in one direction while the other flight moves in the opposite direction a like distance. As previously suggested the brackets 33 carrying panel 31 are interconnected in one flight of chains 41 whereas brackets 33 carrying panel 32 are interconnected in the other flight of chains 41. A knob 53 is secured to one of the brackets 33 supporting panel 31 and is useful in moving panel 31 and consequently panel 32 from its closed position to its open position, and each of the slings 47 threadedly receives a screw 54, which is effective for moving shaft 46 and consequently adjusting the slack in chains 41.

In operation, referring particularly to Figs. 8 and 9 wherein the principles of the present invention are illustrated, it will be apparent that the movable panels are in counterbalancing relationship so that panel 31 is held in position by the weight of panel 32. This result is obtained since both of the panels are of about equal size and weight, and, of course, some friction is developed in the linkage connecting the opposite ends of the panels which will prevent movement if some difference in weight of panels is present. Because of the counterbalance between panels 31 and 32, the panel 31 can be moved upwardly by knob 53 adjacent top panel 20 with only a minimum of exertion, the panel 32 in turn being consequently moved downwardly adjacent bottom panel 19. An opening in the screen is 75

thus provided for access to the interior of the fireplace. Only a minimum of exertion is likewise required to move panel 31 and consequently panel 32 into their closed and overlapping positions relative to stationary panels 19 and 20 for sealing the opening of the screen.

Because each of the chains 41 are interconnected by shaft 46, the movable panels will move relative to the guide channels without bending and will remain parallel to each other. For instance, if knob 53 is raised, this movement will be transmitted by its adjacent chain 41 to shaft 46 and then to the other chain 41 so that both chains will be caused to move in unison. Of course, the same action will result when the handle 53 is lowered so that the movable panels will always move together in parallel relationship and in opposite directions.

As previously described, the panels 20, 31 and 32 are constructed of heat-treated or tempered glass which does not weaken when subjected to high temperature and which will not break easily when struck with a hard object such as fireplace tools. The use of glass for these panels permits the interior of the fireplace to be observed when the movable panels are in closed position and the panels protect against soot, smoke, and sparks entering the room from the fireplace. The bottom panel 19 is preferably formed of metal and the center section 21 preferably has openings 55 formed therein for permitting the circulation of air through the screen.

By the present invention, a novel fireplace screen is provided which incorporates novel means for movably supporting the panels 31 and 32 relative to the screen frame. It is understood that the principles of the present invention can be utilized by various other closures in addition to fireplace screens and that any suitable material, either opaque or transparent, can be used for any of the panels.

What is claimed is:

1. A fireplace screen comprising a frame having top and bottom stationary panels and upper and lower movable panels, said movable panels extending transversely across the opening in said frame between said stationary panels, means associated with said frame for guiding said movable panels to move in predetermined paths in said frame, the plane of said top panel being offset from the plane of said upper movable panel and the plane of said bottom panel being offset from the plane of said lower movable panel and said upper movable panel being coplanar with said bottom stationary panel whereby the upper movable panel can be moved upwardly to overlap the top panel and the lower movable panel can be moved downwardly to overlap said bottom panel and whereby a four-panel screen having a three-panel thickness is provided, and an endless force transmitting belt carried by said frame, one flight of said transmitting belt being connected with said upper movable panel and the other flight of said transmitting belt being connected with said lower movable panel whereby said upper and lower movable panels will be caused to move in unison in opposite directions with said upper and lower movable panels both on the same side of said top and bottom panels respectively.

2. A fireplace screen comprising a frame having top and bottom stationary panels and upper and lower movable panels, said movable panels extending transversely across the opening in said frame between said stationary panels, means associated with said frame on both sides thereof for guiding said movable panels to move in predetermined paths in said frame, the plane of said top panel being offset from the plane of said upper movable panel and the plane of said bottom panel being offset from the plane of said lower movable panel and said upper movable panel being coplanar with said bottom stationary panel providing a four-panel screen having a three-panel thickness whereby the upper movable panel can be moved upwardly to overlap the top panel and the

lower movable panel can be moved downwardly to overlap said bottom panel, a transverse shaft rotatably carried by said frame adjacent to said top panel, gear wheels fixed to said shaft adjacent to each of said guiding means, a pulley rotatably carried by said frame adjacent to each of said guiding means and adjacent to said bottom panel, and endless force transmitting chains trained around associated gear wheels and pulleys, one flight of each of said chains being connected with said upper movable panel and the other flight of each of said chains being connected to said lower movable panel whereby said upper and lower movable panels will be caused to move in unison in opposite directions.

3. The fireplace screen defined in claim 2 further characterized by each of said movable panels having a mounting bracket fixed to the opposite ends thereof and said mounting brackets being received by said guiding means for guided movement thereon.

4. In a mounting bracket and guide arrangement, a plurality of panels guided thereby in predetermined paths, a common guide member having spaced apart opposed guide edges with a passageway therebetween, a bracket for each panel extending for substantially the height of each panel and being slightly short thereof to allow for overlap of adjacent panel edges, each bracket comprising a channel portion and a neck portion, said channel portion having a pair of spaced sides for receiving therebetween and gripping one end of one of said panels, said neck portion having formed therein opposed guideways providing a T-section guide, said common guide member

5

guide edges engaging said guideways in each of said T-section guides for slidably supporting said bracket thereon, and said channel portion of each of said brackets being displaced to one side of the longitudinal centerline of said bracket to allow for said overlap of adjacent edges of said panels.

5. The invention defined by claim 4 wherein said common guide member is channel shaped in cross section for reception of a force transmitting belt, and each of said 10 bracket T-section guides having a clevis extending into said common guide member and being connectable to a force transmitting belt.
